KNIFE AND KNIFE HOLDER ASSEMBLY IN
VENEER CUTTING MACHINESEricsson H. Merritt, Lockport, N. Y., assignor, by
mesne assignments, to Solem Machine Com-
pany, Rockford, Ill., a corporation of Illinois

Application August 25, 1948, Serial No. 46,083

5 Claims. (Cl. 144—212)

1

This invention relates to the art of cutting and slicing wood veneer; more particularly it relates to an improved knife and knife holder combination to be used with veneer cutting and slicing equipment.

In general practice rotary veneer is produced by revolving a log against a knife whose length is equal to or in excess of the length of the log being cut. Sliced veneer is produced by clamping a flitch to a reciprocating table and moving the table with the flitch past the knife. At each stroke a sheet of veneer is cut from the flitch. In each of the described veneer cutting operations, to prevent the wood from splitting ahead of the knife, a pressure plate is provided to apply pressure to the log just ahead of the knife. Thus, the ribbon of veneer severed from the log by the knife is actually extruded through the slot formed by the knife and the pressure plate. The cross-section of this slot is slightly less than the thickness of veneer being cut. To cut smooth uniform thickness veneer, the slot must be of uniform cross-section and have parallel edges. Furthermore, in the case of rotary veneer the bottom edge of the slot formed by the edges of the knife must be in accurate parallel relationship to the axis of rotation of the log and the top of the slot formed by the pressure plate must be in accurate parallel relationship to the knife edge. Since it is not unusual to cut veneer as thin as fifteen thousandths of an inch in thickness, it is obvious that the tolerances to which the knife must be set are extremely narrow.

Veneer knives are composite structures generally varying in size from $\frac{1}{2}$ inch to $\frac{3}{4}$ inch thick, usually 6 inches to $7\frac{1}{2}$ inches wide when new, and varying in length from 24 inches to 200 inches. Slots are usually provided for bolts used to attach the knives to the lathe or slicer knife carriage. Such a light composite steel section as the knife, and which is usually weakened by slots, will, if placed on edge and supported at both ends, deflect appreciably due to its own weight alone, not to mention the loading incident to cutting. As the knife becomes narrower due to grinding, this deflection materially increases. Thus, the knife itself has little inherent rigidity, when considered as a beam.

Veneer knives contain a considerable amount of internal stresses. Additional stresses are built up in the edge of the knife by the constant peening action of the log striking the knife edge. This is particularly true when irregular shaped logs are being reduced to a cylinder preliminary to the cutting of veneer. Preparatory to a grinding or

sharpening operation on the knife, due to the stresses introduced by the veneer cutting operation, it is often necessary to force the knife to assume a straight line. The bevel of the knife is ground until a sharp cutting edge is produced which is a straight line within the limits of accuracy of the grinder and the perfection of the plane of the face of the knife. This grinding operation to a certain extent releases many of the stresses which were formed in the knife during the cutting operation. When the knife is released from the grinder clamps which hold the knife rigidly in place during the grinding operation, it immediately assumes its natural shape and the cutting edge is no longer a true straight line. Accordingly when this knife is attached to the knife carriage in the veneer-cutting machine, it must be adjusted higher to compensate for the width lost in the grinder and also it must be forced by local adjusting screws provided in the knife carriage, to take such a shape that the cutting edge will be a true straight line parallel to the axis of rotation of the log. This is a time consuming operation requiring a high degree of skill. Thus, according to the method as practiced heretofore of handling veneer cutting knives, a precision alignment of the knife is required for both the grinding operation and for the repositioning of the sharpened knife in its holder on the cutting machine.

It is an object of this invention to provide a knife and knife holder assembly which facilitates the positioning of the knife in a veneer cutting machine so that precision alignment is obtained with a minimum amount of local adjusting.

Another object of this invention is to provide a veneer cutting knife and knife holder assembly which when precision ground will be in perfect alignment without further adjustment when placed in the veneer cutting machine.

It is also an object of this invention to provide an improved knife and knife holder assembly for a veneer cutting machine which eliminates all but a small fraction of the time required to change a knife in a veneer lathe or a veneer slicer.

Further objects will become apparent from the description of the invention and the claims.

These objects are accomplished by means of the applicant's invention which provides an accurately machined rigid steel beam, called the holder, to which a cutting knife is adjustably attached. The veneer cutting knife and knife holder are removable as a unit from the veneer cutting machine. The holder is so constructed as to have a moment of inertia sufficiently great

with respect to the knife to resist deflection of the knife caused by unbalanced stresses therein. Slots are provided in the holder for bolts which are threaded into the knife holding the knife rigidly in place. Holes are also provided in both the holder and the knife attached thereto for the purpose of securely bolting the unit to the veneer cutting machine. Push and pull adjusting screws are provided in the bottom of the holder to facilitate adjustment of the knife in the holder. The machined surfaces of the holder and their cooperative machined surfaces on the veneer cutting machine are so constructed as to maintain a fixed relationship between the surfaces and the line of contact between the cutting edge of the knife and the log or flitch.

With such a construction, during the sharpening operation, the dull or nicked knife, together with its holder, are removed as a unit from the lathe or the slicer. At the grinding wheel, the knife is adjusted with respect to the holder to a distance equal to the amount of knife which must be ground away to produce a new perfect edge. The bevel of the knife while rigidly clamped in its holder, is ground until the distance from the new edge to the locating surfaces on the holder is the correct distance to bring the knife edge to the proper position in the veneer lathe or slicer. The knife and knife holder are then removed from the grinder, and, due to the moment of inertia of the knife holder, the knife edge remains a straight line and does not bow or otherwise deflect due to the internal stresses in the knife. On replacing the resharpened knife and its holder in the veneer cutting or slicing machine so that the locating surfaces of the knife holder are in contact with their cooperative locating surfaces in the cutting machine, the knife edge is automatically in correct adjustment requiring no further manual local adjusting.

The invention will be more clearly understood from the following description wherein:

Figure 1 is the front elevation of a fragmentary length of the knife and knife holder assembly of this invention.

Figure 2 is a transverse section of the knife and knife holder assembly of this invention taken on line 2-2 of Figure 1, supported in a conventional manner in a veneer lathe.

Figure 3 is a transverse section of the knife and knife holder of this invention taken on line 3-3 of Figure 1.

The knife holder 4 is an accurately machined rigid steel beam to which the adjustable veneer knife 5 is attached. Surface 6 of the knife holder and surface 7 of the knife holder seat are accurately machined in parallelism so that the entire length is parallel to the axis of rotation of the log 8 in a veneer cutting lathe. Surfaces 9, 10, 11, and 12 of the knife holder are accurately machined so that they are perpendicular to surface 6. The knife holder 4 is equipped with a plurality of unthreaded circular holes 13, alternating with a plurality of oval shaped slots 14. The holes 13 are so ledged to accommodate clamping bolts 15 whereby the knife holder 4 and knife 5 may be rigidly attached to back plate 16 in such a manner that surface 6 is exactly positioned on surface 7. Veneer knife 5 contains a plurality of slots 17 so positioned and of such a size to permit an unobstructed passage of bolt 15. Alternating with slots 17 on knife 5 are a plurality of rows of threaded holes 18, each row of holes consisting of three and being on a center line perpendicular to the length of knife edge, and

each hole being of such a size to accommodate bolt 19 when placed through slot 14 of the knife holder, with slot 14 being so ledged to permit knife 5 to be rigidly attached to holder 4 by tightening bolt 19, and adjusting by means of push screw 20 or pull screw 21, for which a threaded hole and a clear hole are provided in holder 4, respectively. Screws 20 and 21 are so constructed that they do not extend beyond surface 6 of holder 4.

In operation, log 8 is rotated against knife edge 22 cutting a sheet of veneer which is extruded through the slot one side of which is formed by the edge of pressure plate 23, which is held in place by pressure plate holder 24, and the other side of which is formed by the cutting edge 22 of veneer knife 5. On requiring sharpening, bolts 15 are removed and knife holder 4 and veneer knife 5 are removed as a unit from the lathe for grinding. At the grinding wheel, bolts 19 are loosened slightly and by means of screws 20 and 21 the knife is elevated vertically until the distance between knife edge 22 and surface 6 is sufficiently greater to permit grinding edge 22 far enough to remove all of the imperfections and then is accurately adjusted and tightened so that the distance between surface 6 and the newly sharpened knife edge 22 will be equal to the precisely set and predetermined distance on the lathe. Inasmuch as the knife holder 4 has a sufficient moment of inertia with respect to the knife to resist deflection of the knife due to the stresses and strains set up in the knife during the cutting and grinding operations, when the knife holder and the knife which has been accurately aligned at the grinding operation is repositioned in the lathe, no further adjustment of the knife 5 is required. Therefore, since the distance from surface 7 to knife edge 22 is constant, and since this distance is accurately set in the grinding operation, and since the holder is of such a size to resist deflections of the knife due to strains, all that remains after the grinding operation is merely the repositioning of the knife and knife holder assembly in the veneer lathe. Thus, instead of the procedure as practiced heretofore of requiring two accurate alignments of the knife, one during the grinding operation and another during the repositioning of the sharpened knife in the lathe, only one alignment is necessary, thereby greatly reducing the requirements of highly skilled techniques.

According to heretofore practiced techniques, a dull or nicked veneer knife requiring resharpening is removed singly from the cutting machine. An experienced grinder then grinds or resharpenes the knife forcing the knife edge by local adjustment to assume a true straight line. The grinder then releases the knife from the grinder carriage and returns the knife to the slicer or veneer lathe. However, on releasing the knife from the grinder, due to the unbalanced stresses in the knife and the lack of rigidity of the knife blade, the true straight cutting edge is lost due to deflections. Consequently, when this knife is again positioned in the cutting lathe or slicer, realignment by local adjusting of the knife is again necessary to force the cutting edge of the knife into a true straight line. Such an aligning and adjusting operation requires a skilled craftsman. With the knife and knife holder assembly of this invention, it is this second local adjustment of the knife that is eliminated. Inasmuch as the cutting edge has been properly aligned during the grinding operation and is rigidly held in place by

the holder that has a sufficient moment of inertia to resist subsequent deflections of the knife and that such holder is so constructed with regard to the veneer cutting machine as to maintain a fixed relationship with the line of contact between the cutting edge of the knife and the log or flitch, further adjustment of the knife is unnecessary when the knife and its holder is repositioned in the veneer cutting machine.

What is claimed is:

1. In a veneer cutting machine comprising a carriage adapted for rigidly supporting the holder of a veneer cutting knife, said carriage including a back plate, a knife and knife holder combination assembly installable and removable as a unit on and from the carriage respectively, means adjustably attaching said knife to said knife holder on that side of the holder adapted to face the back plate, said knife holder having a moment of inertia sufficiently great to resist deflection of the attached knife, said knife holder having accurately machined locating surfaces co-operative with accurately machined locating surfaces on the knife holder carriage whereby the distance of the cutting edge of said knife from the said locating surfaces on the knife holder carriage may be accurately set and maintained by said adjustable attaching means before said assembled knife holder and knife is positioned on the carriage, and means fastening said assembled knife holder and knife to the back plate on the carriage comprising bolts extending from said knife holder to the back plate through aligned apertures in said knife and which also serve to clamp said knife between said knife holder and back plate.

2. In a veneer cutting machine, comprising a carriage adapted for rigidly supporting the holder of a veneer cutting knife, the carriage including an elongated back plate, the improvement consisting of a knife and knife holder combination assembly installable and removable as a unit on and from the carriage respectively, said knife and knife holder being both elongated like the back plate, said knife holder having accurately machined locating surfaces arranged for abutment with accurately machined locating surfaces on the carriage, a plurality of bolts, each of which extends through aligned apertures in said knife holder and knife, one of said aligned apertures being slotted for adjustably securing said knife to said holder on that side thereof adapted to face the back plate, and a plurality of other bolts each of which extends through aligned apertures in said knife holder and knife and into the back plate for rigidly securing the assembled knife and knife holder to the back plate and clamping the knife between the holder and back plate.

3. In a veneer cutting machine, comprising a carriage adapted for rigidly supporting the holder of a veneer cutting knife, the carriage including an elongated back plate, the improvement consisting of a knife and knife holder combination assembly installable and removable as a unit on and from the carriage respectively, said knife and knife holder being both elongated like the back plate, said knife holder having accurately machined locating surfaces arranged for abutment with accurately machined locating surfaces on the carriage, a plurality of bolts, each of which extends through aligned apertures in said knife holder and knife, one of said aligned apertures being slotted for adjustably securing said knife to said holder on that side thereof adapted to face the back plate, said bolts when loosened

permitting adjustment as to elevation of the knife relative to the holder as a whole, screws in longitudinally spaced relation along the holder and engaging said knife for local adjustment of longitudinally spaced portions of the knife in the plane thereof, and a plurality of other bolts each of which extends through aligned apertures in said knife holder and knife and into the back plate for rigidly securing the assembled knife and knife holder to the back plate and clamping the knife between the holder and back plate.

4. In a veneer cutting machine, comprising a carriage adapted for rigidly supporting the holder of a veneer cutting knife, the carriage including an elongated back plate, the improvement consisting of a knife and knife holder combination assembly installable and removable as a unit on and from the carriage respectively, said knife and knife holder being both elongated like the back plate, said knife holder having accurately machined locating surfaces arranged for abutment with accurately machined locating surfaces on the carriage, a plurality of bolts, each of which extends through aligned apertures in said knife holder and knife, one of said aligned apertures being slotted for adjustably securing said knife to said holder on that side thereof adapted to face the back plate, said bolts when loosened permitting adjustment as to elevation of the knife relative to the holder as a whole, a plurality of parallel push screws disposed in the plane of and behind the knife and threaded in the holder at longitudinally spaced points and abutting the knife for local elevation adjustments of longitudinally spaced portions of the knife, a plurality of parallel pull screws in a plane parallel to the plane of the push screws entered with freedom to turn in holes provided therefor in the holder and threaded in holes provided therefor in the knife at longitudinally spaced points between the push screws for local adjustments of longitudinally spaced portions of the knife in the opposite direction to that of the adjustments afforded by said push screws, and a plurality of other bolts each of which extends through aligned apertures in said knife holder and knife and into the back plate for rigidly securing the assembled knife and knife holder to the back plate and clamping the knife between the holder and back plate.

5. In a veneer cutting machine, comprising a carriage adapted for rigidly supporting the holder of a veneer cutting knife, the carriage including an elongated back plate, the improvement consisting of a knife and knife holder combination assembly installable and removable as a unit on and from the carriage respectively, said knife and knife holder being both elongated like the back plate, said knife holder having accurately machined locating surfaces arranged for abutment with accurately machined locating surfaces on the carriage, a plurality of bolts, each of which extends through aligned apertures in said knife holder and knife, one of said aligned apertures being slotted for adjustably securing said knife to said holder, said bolts when loosened permitting adjustment as to elevation of the knife relative to the holder as a whole, a plurality of parallel push screws disposed in the plane of and behind the knife and threaded in the holder at longitudinally spaced points and abutting the knife for local elevation adjustments of longitudinally spaced portions of the knife, a plurality of parallel pull screws in a plane parallel to the plane of the push screws entered with freedom to turn in holes provided therefor in the holder

and threaded in holes provided therefor in the knife at longitudinally spaced points between the push screws for local adjustments of longitudinally spaced portions of the knife in the opposite direction to that of the adjustments afforded by said push screws, and a plurality of other bolts extending through apertures in said knife holder into the back plate for rigidly securing the assembled knife and knife holder to the back plate.
